ABSTRACT

A washing machine includes a cabinet defining a housing with internal components of a conventional automated clothes washer, a door mounted to the cabinet to selectively open/close the opening to the cabinet, and a dispenser in the form of a fill cup assembly in which single or bulk doses of treating chemistry can be received. The fill cup assembly includes a base cup with at least first and second fluid conduits supplying corresponding destinations, and a selector cup defining a pour zone. The selector cup includes an outlet and rotatable relative to the base cup to selectively fluid couple the outlet to the at least first and second fluid conduits.

FIG. 2

FIG .3

FIG .4

1
DISPENSER CUP

**CROSS-REFERENCE TO RELATED
APPLICATIONS**

This application is a continuation of U.S. patent application Ser. No. 15/253,128, filed Aug. 31, 2016, now U.S. Pat. No. 9,863,082, issued Jan. 9, 2018, which is incorporated herein by reference in its entirety.

BACKGROUND

Laundry treating appliances, such as clothes washers, clothes dryers, refreshers, and non-aqueous systems, can have a configuration based on a rotating drum that defines a treating chamber having an access opening through which laundry items are placed in the treating chamber for treating. The laundry treating appliance can have a controller that implements a number of pre-programmed cycles of operation having one or more operating parameters.

In some laundry treating appliances, the dispenser is in the form of a cup mounted on the surface of the cabinet. Such dispensers typically have at least one cup that defines a pour zone for a specific treating chemistry or dispensing functions such as a single use or bulk dispenser. It will be desirable for a washing machine to use minimal surface space as pour zones for various types of treating chemistry and dispensing functions.

BRIEF SUMMARY

In one aspect, embodiments of the current disclosure relate to a laundry treating appliance having a cabinet defining an interior and having an access opening providing access to the interior. A treating chamber is located within the interior. The cabinet carries a treating chemistry dispenser fluidly coupled to the treating chamber. A treating chemistry fill cup assembly has a base cup with first and second fluid conduits supplying corresponding first and second destinations, and a selector cup having an outlet and movable relative to the base cup to selectively fluid couple the outlet to the first and second fluid conduits.

BRIEF DESCRIPTION OF THE DRAWINGS

In the drawings:

FIG. 1 is a front view of a laundry treating appliance in the form of an automatic washing machine having a cabinet with a door shown in an opened condition, and with a dispenser assembly.

FIG. 2 is a schematic view of a treating chemistry fill cup assembly.

FIG. 3 is a perspective view of the treating chemistry fill cup assembly.

FIG. 4 is an exploded, perspective view of the treating chemistry fill cup assembly of FIG. 3.

DETAILED DESCRIPTION

Referring now to FIG. 1, a first embodiment in accordance with the present disclosure is illustrated as a laundry treating appliance in the environment of a vertical axis automatic clothes washing machine 10. Although much of the remainder of this application will focus on the embodiment of an automatic clothes washing machine, the illustrative embodiments have utility in other environments, including other laundry treating appliances or other top loading

2

appliances with a single use or bulk dispenser. Depending on the configuration, it is possible for the embodiments to have applicability in horizontal axis washing machines and other front loading appliance.

5 The washing machine 10 shares many features of a conventional automated clothes washer, which will not be described in detail herein except as necessary for a complete understanding of the illustrative embodiments in accordance with the present disclosure. The washing machine 10 has a 10 rotatable drum 12 that defines a treating chamber 14 for receiving the laundry and rotates about a generally vertical axis.

A tub 15 receives the drum 12 and holds liquid for use in a treating cycle of operation. The tub 15 can rotatably mount 15 the drum 12. The tub 15 can be associated with a sump for holding a liquid used during a cleaning cycle. The sump can be normally connected to a drain (not shown) to provide a flow path for removing the liquids.

A cabinet 16 can define a housing within which a suspension system (not shown) is provided for suspending the tub 15 within the cabinet 16. The cabinet 16 can be a housing having a chassis and/or a frame to which panels are mounted to define an interior, enclosing components typically found in a conventional washing machine, such as motors, pumps, 25 fluid lines, controls, sensors, transducers, and the like. Such components will not be described further herein except as necessary for a complete understanding of the disclosure.

A closure in the form of a door 18 is mounted to the cabinet 16 via a hinge 17. The door 18 can be rotated about 30 the hinge 17 to selectively close an opening 19 to the treating chamber 14. Both the tub 15 and a drum 12 can be located within the interior of the cabinet 16.

The washing machine 10 can also be provided with a dispenser assembly 22 for dispensing treating chemistry to 35 the treating chamber 14 for use in treating the laundry according to a cycle of operation. The dispenser assembly 22 is illustrated to include an integrated single use and bulk dispensing system.

The dispenser assembly 22 includes at least one treating 40 chemistry fill cup assembly 24 and at least one bulk reservoir 26. The fill cup assembly 24 is mounted to the cabinet 16 in one of the corners of the surface surrounding the access opening 19 to the treating chamber 14. The fill cup assembly 24 can be rotated to selectively direct treating chemistry into 45 the treating chamber 14 for a single use application or storage in the associated bulk reservoir 26 for bulk dispensing application. As shown in the illustration, the fill cup assembly 24 can be configured to direct treating chemistry to more than two destinations. For instance, fluid can be 50 directed to the treating chamber 14 via fluid conduit 31a and to multiple bulk reservoirs 26 via fluid conduit 31b and 31c. These reservoirs 26 are used for containing various treating chemistries, such as but not limited to liquid detergent, bleach, and fabric softener. These reservoirs 26 can be 55 located interiorly or exteriorly of the cabinet 16.

Referring to the schematic diagram of FIG. 2, the fill cup assembly 24 comprises a base cup 32 with at least first and second fluid conduits 33a,b supplying corresponding destinations, and a selector cup 34 defining a pour zone 25. The 60 selector cup 34 includes an outlet 36 and rotatable relative to the base cup 32 to selectively fluidly couple the outlet 36 to the at least first and second fluid conduits 33a,b. As shown in the figure, the first fluid conduit 33a can be directed to the associated first destination and the second fluid conduit 33b can be directed to the second destination. By aligning the outlet 36 of the selector cup 34 to the fluid conduit 33a of the base cup 32, a single passage for the flow of fluid through 65

fluid conduit 33a is created while passage to fluid conduit 33b is closed. Treating chemistry poured into the selector cup 34 can be directed exclusively to the first destination. Alternatively, the selector cup 34 can be rotated clockwise or anti-clockwise to selectively align the outlet 36 to create a passage for fluid to flow through the fluid conduit 33b into the second destination.

Referring to FIGS. 3 and 4, the selector cup 34 and base cup 32 have complementary shapes wherein the selector cup 34 is at least partially received within the base cup 32. A rotatable shaft 38 with over-the-center spring mechanism passes through the base cup 32 and is rotatable by the selector cup 34. The rotatable shaft 38 with over-the-center spring mechanism biases the base cup 32 and selector cup 34 towards one another and act as a detent mechanism between the base cup 32 and selector cup 34 to divide the rotation into specific increments. As shown in FIG. 4, the specific increments can be configured to align the outlet 36 of the selector cup 34 to each fluid conduits 33a,b of the base cup 32. The specific increments can also be configured to align the outlet 36 to a sealed region of the base cup 32 to create a closing position without having a separate lid.

The fill cup assembly 24 utilizes a single pour zone 25 to direct treating chemistries to multiple destinations. This feature improves the ease of use and maintains aesthetic value with a clean surface finish surrounding the access opening 19 to the treating chamber 14. Furthermore, it will not be necessary to decrease the size of the access opening 19 of the treating chamber 14 due to having multiple pour zones for various chemistries and dispensing function.

Although the embodiment of the present invention have been shown and described, it would be appreciated by those skilled in the art that changes may be made in these embodiments without departing from the principles and spirit of the invention, the scope of which is defined in the claims and their equivalents.

The invention claimed is:

1. A laundry treating appliance comprising:
a cabinet defining an interior and having an access opening providing access to the interior;
a treating chamber located within the interior for receiving laundry for treatment according to a cycle of operation; and
a dispenser assembly having multiple conduits supplying different destinations and a movable selector compartment having a treating chemistry reservoir with an outlet selectively coupled with the multiple conduits; wherein the selector compartment is movable to fluidly couple with a selected one of the multiple conduits to fluidly couple the treating chemistry reservoir to the destination corresponding to the selected conduit.
2. The laundry treating appliance of claim 1 wherein the selector compartment comprises a selector cup.

3. The laundry treating appliance of claim 2 comprising a base cup that is configured to receive the selector cup therein, wherein the selector cup is movable relative to the base cup to fluidly couple the selector compartment with each of the multiple conduits.

4. The laundry treating appliance of claim 1 wherein the multiple conduits supplying different destinations comprises at least two conduits supplying at least two different destinations.

5. The laundry treating appliance of claim 1 wherein a first one of the multiple conduits supplies a bulk reservoir and a second one of the multiple conduits supplies the treating chamber.

10 6. The laundry treating appliance of claim 1 wherein at least one of the multiple conduits supplies a destination located exteriorly of the cabinet.

15 7. The laundry treating appliance of claim 1 wherein the selector compartment is movable to direct a first type of treating chemistry to a first one of the multiple conduits and to direct a second type of treating chemistry, different than the first type, to a second one of the multiple conduits.

20 8. The laundry treating appliance of claim 1 wherein the multiple conduits comprise at least two conduits, each of the at least two conduits fluidly coupled with a bulk reservoir.

25 9. A dispenser assembly for dispensing treating chemistry in a laundry treating appliance comprising a treating chamber for receiving laundry for treatment according to a cycle of operation, the dispenser assembly comprising:

30 a movable selector compartment having a treating chemistry reservoir with an outlet; and
multiple conduits fluidly coupled with different destinations;
wherein the selector compartment is movable to fluidly couple the selector compartment with each of the multiple conduits to fluidly couple the treating chemistry reservoir to the destination corresponding to the selected conduit.

10. The dispenser assembly of claim 9 wherein the selector compartment comprises a selector cup.

11. The dispenser assembly of claim 10 comprising a base cup that is configured to receive the selector cup therein, wherein the selector cup is movable relative to the base cup to fluidly couple the selector compartment with each of the multiple conduits.

40 12. The dispenser assembly of claim 9 wherein the multiple conduits comprise at least two conduits, each of the at least two conduits configured to be fluidly coupled with a bulk reservoir.

45 13. The dispenser assembly of claim 9 wherein a first one of the multiple conduits is configured to be fluidly coupled with a bulk reservoir and a second one of the multiple conduits is configured to be fluidly coupled with the treating chamber.
